UNITED STATES PATENT OFFICE

92,887

DESIGN FOR A TOY

Grace M. H. Dubbles, Lincoln, Nebr.

Application May 21, 1934, Serial No. 51,874

Term of patent 7 years

To all whom it may concern:

Be it known that I, GRACE M. H. DUBBLES, a citizen of the United States, residing at Lincoln, in the county of Lancaster, and State of Nebraska, have invented a new, original, and ornamental Design for Toys, of which the following is a specification, reference being had to the accompanying drawing, forming part thereof.

Figure 1 is a view in front elevation, Figure 2 is a view in side elevation, and Figure 3 is a view in rear elevation, showing my new design.

I claim:

The ornamental design for a toy, as shown.

GRACE M. H. DUBBLES.
